UNITED STATES PATENT OFFICE.

MALCOLM S. SIMPSON, OF PITTSBURGH, PENNSYLVANIA, ASSIGNOR TO PRESSED STEEL CAR COMPANY, OF PITTSBURGH, PENNSYLVANIA, A CORPORATION OF NEW JERSEY.

MINE-CAR.

1,176,782.

Specification of Letters Patent.

Patented Mar. 28, 1916.

Application filed July 29, 1915. Serial No. 42,656.

To all whom it may concern:

Be it known that I, MALCOLM S. SIMPSON, a citizen of the United States, residing at Pittsburgh Athletic Association, Pittsburgh, in the county of Allegheny and State of Pennsylvania, have invented certain new and useful Improvements in Mine-Cars, of which the following is a specification.

An object of the invention is to provide a simple, light and strong underframe and construction for mine or like cars which will withstand without substantial damage, the heavy shocks and jars to which a car of this type is subjected, and also protect from damage the remainder of the underframe and the car body.

Another object of the invention is to provide an efficient bumper for mine cars which if damaged may be easily and quickly removed or replaced.

A further object of the invention is to provide novel means for removably securing a bumper to a mine or like car.

With the above and other objects in view the invention resides in the construction, arrangements and combinations of parts hereinafter described and claimed.

Referring now to the drawings, in which like reference characters refer to like parts, Figure 1 is a plan view of a portion of a car constructed in accordance with the invention; Figs. 2 and 3 are side and end elevational views respectively of the same; Fig. 4 is a cross sectional view taken on the line 4—4 of Fig. 1; Fig. 5 is a longitudinal sectional view taken on the line 5—5 of Fig. 1; and Figs. 6 and 7 are end and side elevational views respectively of a car embodying a modification of the invention.

Referring now in detail to the drawings, 1, 1 indicates spaced sill members which may be of any suitable form, but as shown in the drawings are preferably of channel form in cross section. These sill members preferably terminate short of the ends of the car body, but it will be understood that they may extend for the full length of said body.

2 indicates a member which extends between the sills 1, 1 in a direction transversely of the car and at its ends is provided with flanges 3, 3 which are secured to the webs of such sills. This member 2 may be of any suitable form, but is preferably of Z form in cross section, having its web 4 disposed vertically and its top and bottom

flanges 5 and 6 respectively, disposed horizontally in opposite directions, the flange 5 being disposed in a direction toward the transverse centerline of the car and the flange 6 being disposed in a direction toward the end of the car. Seated on and secured to the flange 6 of the transverse member 2, are members 7, 7, which extend outwardly to the end of the car. These members are preferably of Z form in cross section having their webs 8, 8 disposed vertically and their top and bottom flanges 9 and 10 respectively disposed horizontally in opposite directions, the flange 9 of each member being disposed in a direction toward the side of the car and the flange 10 being disposed in a direction toward the longitudinal centerline of the car.

11 indicates the floor which preferably comprises a flat plate which extends from end to end of the car body and is preferably secured to the upper flanges 12 of the sills 1, 1, the upper flange 5 of the member 2, and the upper flanges 9 of the members 7, 7, thus assisting in rigidly connecting all of said members.

13 indicates a buffer beam which is preferably of wood and which preferably comprises a plurality of sections, which are supported at their inner ends by the flange 6 of the transverse member 2 and may be secured to such flange by bolts 14, or other suitable means. This buffer beam extends outwardly from the member 2 to a point beyond the end of the car body and at its outer end is provided with a guard or buffer plate 15 which is of U or other suitable section. This beam is supported, longitudinally of the car at its side portions, by the flanges 10 of the members 7, 7. To prevent the spreading of the members 7, 7 when the car receives a heavy end shock and to further support the sections of the buffer beam, bolts 16 are provided which extend transversely of the car and pass through the webs 8 of the members 7, 7.

At or near the end of the car body a transverse member 17 is provided which, as shown in Figs. 1, 2 and 3 of the drawings, is preferably of channel form in cross section, but as shown in Figs. 6 and 7 of the drawings, this member may be in the form of a flat plate. This member is provided with vertical end portions 18, 18 which are preferably secured to the side walls 19, 19

of the car body, and is also provided with a horizontal portion 20, which extends beneath and supports the end portions of the buffer beam and the members 7, 7. The buffer beam is secured between the floor 11 and the member 17 by vertical bolts 21. At the end of the car body and at each side thereof a gusset member 22 may be provided which may be secured to the floor 11, member 7 10 and the member 17, thus forming a strong connection between the floor and members.

As shown in Figs. 1, 2 and 3 of the drawings, the end wall of the car body may comprise a door 23, or as shown in Figs. 6 and 15 7 may comprise an end plate 24 which may be connected with the side walls 19. It will be understood that the construction of the underframe may be identical at both ends of the car, or if desired the underframe at one 20 end of the car may be constructed in accordance with Figs. 1, 2 and 3 of the drawings, and at the other end constructed in accordance with Figs. 6 and 7 of the drawings.

I do not wish to be limited to the exact 25 construction of the end framing body and bumpers as described in the specification, for it will be apparent to those skilled in the art to which this invention appertains, that many changes may be made without departing 30 from the spirit and scope of the invention as set forth in the appended claims.

Having thus described the invention, what I claim as new and desire to secure by Letters Patent is:

35 1. In a mine car, spaced sill members, a transverse member between and secured to said sill members, longitudinal members extending outwardly from said transverse member to the end of the car and a buffer 40 beam carried by said transverse and longitudinal members.

2. In a mine car, spaced sills, a transverse member extending between and secured to said sills, side walls, a transverse member 45 secured to said side walls, and a buffer carried by said transverse members.

3. In a mine car, spaced sills, a Z shaped member extending between and secured to said sills, a buffer beam resting on said 50 member, and means for removably securing said beam to said member.

4. In a mine car, spaced sills, a Z shaped member secured between said sills, Z shaped members secured to said member, and a buffer beam removably carried by said Z 55 shaped members.

5. In a mine car, spaced sills, a member 60 extending transversely of said car and secured between said sills, a transverse member at the end of the car, spaced longitudinal members carried by said transverse members, and a buffer beam carried by said longitudinal and transverse members.

6. In a mine car, spaced sills, a member 65 extending transversely of said car and se-

cured between said sills, a transverse member at the end of the car, spaced longitudinal members secured to said transverse members, and a buffer beam removably carried by said longitudinal and transverse members. 70

7. In a mine car, spaced sills, a transverse member secured between said sills, longitudinal members secured to said transverse member, said sills and members having upper and lower flanges, a floor secured to said 75 upper flanges and a buffer beam carried by said lower flanges.

8. In a mine car, a transverse underframe member, a plurality of spaced longitudinal members secured to said transverse member, 80 a floor secured to said transverse and longitudinal members, a transverse member at the end of the car, and gusset members interposed between and secured to said longitudinal members, floor and last mentioned 85 transverse member.

9. In a mine car, spaced sills, a transverse member secured between said sills, spaced longitudinal members secured to said transverse member and extending to the end of 90 the car, and a buffer beam carried by and filling the space between said transverse and longitudinal members.

10. In a mine car, spaced sills, a transverse member secured between said sills, 95 spaced longitudinal members secured to said transverse member and extending to the end of the car, and a buffer beam carried by and filling the space between said transverse and longitudinal members, said buffer beam comprising a plurality of removable sections. 100

11. In a mine car, spaced sills, a transversely extending member secured between said sills, spaced longitudinal members secured to said transverse member, said transverse and longitudinal members having lower flanges and a buffer beam carried by 105 said flanges.

12. In a mine car, spaced sills, a transversely extending member secured between 110 said sills, spaced longitudinal members secured to said transverse member, said members having upper and lower flanges, a floor secured to said upper flanges and a buffer beam carried by said lower flanges. 115

13. In a mine car, spaced sills, a transversely extending member secured between said sills, spaced longitudinal members secured to said transverse member, said members having upper and lower flanges, a floor 120 secured to said upper flanges and a buffer beam carried by said lower flanges, said buffer beam filling the space between said members and between said floor and lower flanges. 125

14. In a mine car, a plurality of spaced transverse flanged underframe members, spaced longitudinal flanged members secured to said transverse members, and a buffer beam carried by said flanges. 130

15. In a mine car, spaced sills, a transverse member secured to said sills, spaced longitudinal members secured to said transverse member, said longitudinal and transverse members having upper and lower flanges, a floor plate secured to the upper flanges of said members and a buffer beam carried by said lower flanges beneath said floor.
16. In a mine car, spaced sills, a transverse member secured between said sills, spaced longitudinal members having their inner end portions secured to said transverse member, a floor plate secured to said sills

and all of said members, side walls secured 15 to said sills and floor plate, a transverse member connected with said side walls adapted to extend below and support the outer end portions of said longitudinal members, and a buffer beam removably secured between said longitudinal members. 20

In testimony whereof I affix my signature in presence of two witnesses.

MALCOLM S. SIMPSON.
